CORNCRIB AND GRANARY

Peter J. Hegnes, Canton, S. Dak.

Application July 27, 1935, Serial No. 33,577

8 Claims. (Cl. 20—5)

This invention relates to corn cribs and granaries and the primary object thereof is to provide a structure of this kind which may be easily and quickly converted for use either as a corn crib or granary.

Further the invention aims to provide a novel structure of this character which has improved means for controlling the drying of the corn, when used as a crib, so that such drying occurs either rapidly or slowly, as may be desired.

Still further the invention aims to provide a novel and economical roof construction wherein the parts are assembled in a more compact and simplified manner.

Another object of the invention is to provide a knockdown structure of this type wherein the parts can be constructed and readily assembled and taken apart.

In the drawings:

Fig. 1 is a vertical fragmentary section of the invention;

Fig. 2 is a section on line 2—2 of Fig. 1;

Fig. 3 is a section on line 3—3 of Fig. 2;

Fig. 4 is a fragmentary top plan view showing one of the roof sections with the roofing sheathing omitted;

Fig. 5 is a section on line 5—5 of Fig. 1; and

Fig. 6 is a fragmentary vertical sectional view of a modified form of side wall.

In proceeding in accordance with the present invention, uprights 1 of generally T-shape are erected on the floor 2 in spaced relation. Cross strips 3 are arranged in the spaces between the uprights and have their ends abutting the corners at the heads and webs of the uprights as shown in Fig. 3. The strips 3 are held in vertically spaced relation by spacing blocks 4, shown in Figs. 1 to 3. Due to the convergent relation of adjacent webs of the uprights, as shown in Fig. 3, and tie wires or cables 5 equipped with turn-buckles 6, which elements 5 encircle and tightly engage about the heads of the uprights, these parts may be held firmly together without the necessity of other fasteners, such as nails or the like. Metal plates 7 which act as air-control shutters to adjust the air spaces between adjacent strips 3 so as to govern the speed of

drying of corn, are employed and are provided with slots 8, through which screws 9 project into the strips 3. When used as a granary, the shutters are adjusted to completely close the spaces between adjacent strips.

The roof structure embodies, as shown in Fig. 4, pairs of radial rafters 10 and segmental units or sections composed of side rails or strips 17,

divergently related and connected by cross-strips 11 and 12 the latter each having a longitudinal groove 13 to receive the uppermost adjacent strip 3 thereby to hold the roof segments in position. The upper ends of the rafters 10 abut and are secured to the periphery of a hollow or tubular filling crown 14 by means of lag screws 15. A closure 16 is provided for the crown and is removable therefrom to afford access to the lag screws 15 in assembly and knocking down of 10 the structure. The strips 17 are connected by metal roofing sheathing 18, which latter at one side have offset parts 19 to overlap the sheathing of adjacent units to provide weatherproof joints, see Figs. 2 and 5.

In order to hold the outer ends of adjacent strips 17 on opposite sides of the rafters, U-shaped clamps 20 are employed which receive the rafters therein, in assembly, the ends of the clamps being turned outwardly and secured to 20 the strips on their under sides by bolts 21. By use of these clamps it is not necessary to perforate the rafters at their lower ends, but at their upper ends the rafters and strips 17 are perforated to receive cross-bolts 22 which rigidly connect these parts.

Steel pins 23 are rigidly secured to the upper ends of the uprights 3 and loosely engage in openings 24 formed in the undersides of the rafters so as to hold the lower ends of the rafters 30 in place during assembly, and finally ties 25 are bolted at 26 to the uprights and rafters 10.

In Fig. 6 a modified form of the invention is depicted and wherein tongue and groove connections 27 are employed between cross-strips 3' of 35 the uprights 1' that correspond to uprights 1 and to the strips 3, of Figs. 1 to 5, so as to form a solid wall construction in cases of use solely as a granary.

From the foregoing it will be evident that an 40 economical and compact structure is provided enabling the parts to be easily and quickly assembled and knocked-down. The tubular member 14 provides a filler opening or inlet for the material, as well as functioning as an anchor for 45 the rafters and roof sections.

What is claimed is:

1. In a structure of the type set forth, a series of spaced T-shaped uprights, the webs of which converge inwardly, cross-strips in the spaces between the uprights engaging in the corners between the heads and webs thereof, spacing blocks between the strips also engaged in said corners to hold the strips vertically spaced from each other, shutters, means to connect the shutters 55

for vertical adjustment to the strips thereby to vary or completely close the space between adjacent strips, a roof connected to the uprights and tie wires having turn-buckles encircling the 5 uprights to frictionally hold the uprights, strips and spacing blocks in assembled relation.

2. In a structure of the type set forth, a series of spaced T-shaped uprights, the webs of which converge inwardly, cross-strips in the spaces between the uprights engaging in the corners 10 between the heads and webs thereof, spacing blocks between the strips also engaged in said corners to hold the strips vertically spaced from each other, shutters, means to connect the shutters 15 for vertical adjustment to the strips thereby to vary or completely close the space between adjacent strips, and a roof connected to the uprights.

3. In a structure of the type set forth, a series of T-shaped uprights, cross-strips in the spaces 20 between the uprights, the webs of the uprights converging inwardly, cross-strips having ends which are engaged in the corners between the heads and webs of the uprights, and tie wires enclosing the uprights to hold the uprights and 25 strips in their said assembled relation.

4. In a structure of the type set forth, side walls having uprights, a roof including a central tubular crown, radial spaced rafters engaged at 30 one end with the periphery of the crown, lag screws operable from within the crown and engaged in the said ends of the rafters, segmental roof sections having side rails engaged in the spaces between adjacent rafters, cross-strips connecting the rails and having grooves receiving 35 the upper ends of the side walls, means to connect the uprights to the rafters, transverse bolts to connect the upper ends of the rails of the roof sections to the uprights, and U-clamps receiving the rafters and connected to said rails 40 of the roof sections on opposite sides of the rafters.

5. In a structure of the type set forth, side walls having uprights, a roof including a central tubular crown, radial spaced rafters engaged at

one end with the periphery of the crown, lag screws operable from within the crown and engaged in the said ends of the rafters, segmental roof sections having side rails engaged in the spaces between adjacent rafters, cross-strips connecting the rails and having grooves receiving the upper ends of the side walls, means to connect the uprights to the rafters, and means to hold the roof sections in position relative to the rafters.

6. In a structure of the type set forth, side walls having uprights, a roof including a central tubular crown, radial spaced rafters engaged at one end with the periphery of the crown, lag screws operable from within the crown and projected into the said ends of the rafters, segmental roof sections having side rails disposed in the spaces between adjacent rafters and abutting the opposite side faces of the latter, means to connect the uprights to the rafters, and means to connect the rails of the roof sections to the rafters.

7. In a structure of the type set forth, side walls, a roof including a central tubular crown, spaced rafters radiating from the crown and having inner ends abutting the periphery of the crown, means to hold the rafters in position relative to the crown, segmental roof sections in the spaces between the rafters having side rails abutting the side faces of adjacent rafters, means to secure the rails of the roof sections against the rafters, and means to connect the rafters to the side walls.

8. In a structure of the type set forth, side walls having uprights, a roof including radial spaced rafters, means to connect the inner ends of the rafters, segmental roof sections having side rails disposed in the spaces between adjacent rafters and abutting the latter, said sections having grooves receiving therein the upper ends of the side walls, tie means secured to the uprights and to the rafters, and means to secure the side rails to the rafters.

PETER J. HEGNES.
